EYELASH CURLER

William R. Tuttle and Charles W. Stickel,
Rochester, N. Y., assignors to The Kurlash
Company, Inc., Rochester, N. Y., a corporation
of New York

Application February 28, 1934, Serial No. 713,268

12 Claims. (Cl. 132—32)

This invention relates to an eyelash curler or crimper embodying the invention of United States Patent No. 1,699,084 dated January 15, 1929, and is intended to serve as a specific improvement thereon.

In the eyelash curler embodied in the above United States Patent No. 1,699,084, the operative jaws are connected to two crossed levers pivotally connected with each other and adapted to be closed manually. In accordance with such structure the distance between the opposing edges of said jaws when separated to the maximum extent measures the degree of clearance for the insertion of the eyelashes.

It has been found that most eyelashes are curled in the first instance before a fresh application of the eyelash curler or crimper and that where the clearance between the said two jaws is insufficient, there is a necessity for straightening out the eyelashes.

One of the objects of the present invention is the provision of a structure whereby such clearance between the cooperating jaws at the limit of separation is increased to the maximum.

A further object of the invention is the provision of a novel definite structure for the more efficient and more economical linkage between the movable jaw and an operative lever of the said eyelash curler.

Still another object of the invention resides in the provision of a novel structure whereby the stationary jaw of the eyelash curler herein is made more rigid and more resistant to the upward thrust of the movable jaw thereagainst.

A still further object of the invention resides in the provision of a novel structure wherein those portions of the levers manually operated can be and are more easily lacquered.

These objects and other incidental ends and advantages will hereinafter appear in the following disclosure and as pointed out in the appended claims.

Accompanying this specification is a drawing showing a preferred form of the invention herein, wherein corresponding reference characters designate corresponding parts throughout the several views and wherein:

Figure 1 is a rear elevational view of a preferred form of an eyelash curler in operative and closed position;

Figure 2 is a side elevation of Figure 1;

Figure 3 is a side elevational view of the eyelash curler herein in open position adapted to receive the eyelashes;

Figure 4 is a front elevational view of Figure 2 as seen from the plane 4—4;

Figure 5 is a sectional view of Figure 2 through the plane 5—5 of Figure 2;

Figure 6 is a fragmentary detail partly in section of the movable jaw of the eyelash curler showing part of a channel for the insertion of a rubber facing centrally grooved and showing part of the mounting of said movable jaw.

In accordance with the invention and in accordance with the accompanying drawing, a supporting lever preferably constructed of a single piece of metal wire is provided, doubled upon itself to form juxtaposed members 15 and 16 at the lower portion, the said juxtaposition being carried out by the formation of a loop 17 so that a substantial space is effectuated between the said juxtaposed members 15 and 16. The said supporting lever at the upper part of members 15 and 16 is preferably flattened as represented by numerals 15' and 16' for a short distance to serve as a mounting for a cooperating movable lever as will hereinafter appear. Extending from the flattened portions of the supporting lever and more specifically from members 15' and 16' thereof are bifurcating posts 18 and 19 respectively developing into vertical and parallel arms 18' and 19'. Near the terminals of parallel arms 18' and 19' is affixed a stationary upper jaw 23 constructed preferably of a thin strip of metal having a rounded lower edge which is curved horizontally and vertically, while the width of said strip is thickened intermediate the ends of said upper stationary jaw. Said jaw 23 is affixed to the parallel arms 18' and 19' by the ordinary means such as a riveting thereto at flattened portions of the upper extremities of said parallel arms 18' and 19'.

The movable lever is composed preferably of a single piece of wire doubled upon itself to form members 10 and 11 juxtaposed by means of a lower continuous loop 12. The upper portions of members 10 and 11 form extended and flattened plates 13 and 14, said plates at the inner ends being pivotally mounted between aforementioned flattened members 15' and 16' by means of connecting pin 29.

Members 10 and 11 of the movable lever are similarly distanced in the juxtaposed relation thereof while the flattened upper portions 13 and 14 are obtusely offset from the members 10 and 11 as best shown in Figures 2 and 3 of the accompanying drawing.

Numeral 20 represents a lower movable jaw which is curved horizontally and vertically and

which preferably consists of an upwardly opening channel and a facing 22 of rubber or other elastic or resilient material secured in this channel and projecting with its upper edge above the side walls of the channel, this channel and facing being both curved horizontally and vertically parallel with the curvature of the upper jaw. The said rubber or other elastic or resilient material is provided with an intermediate groove 23 along the length of facing 22 thereof. The said lower movable jaw is mounted preferably on the parallel arms 18' and 19' of the supporting lever so as to slide lengthwise thereon toward and from the fixed upper jaw 23. The opposite ends of the movable jaw 20 are flattened, to produce horizontal sleeves 21 preferably formed integrally with and at the lower edge of said jaw 20. These novel sleeves are mounted to slide freely on the parallel arms or guide bars 18' and 19' and separated to maintain the upper stationary jaw and the lower movable jaw in parallelism with each other as the movable jaw moves toward and away from the stationary jaw.

Movable jaw 20 is connected to the movable lever at the flattened upper portions 13 and 14 thereof by means of a linking structure. The said linking structure is composed preferably of a single piece of wire passing through orifices at the outer terminals of flattened portions 13 and 14 of the movable lever, the terminals of said piece of wire being connected to the movable jaw 20 at the lower edge thereof. The said linking structure is best represented on Figure 4 wherein the link extends upwardly and divergently to form lower arms 24 and 25 and upper and rearwardly greatly offset arms 26 and 27 (Fig. 2), the diverging members of said links being connected by a cross bar 28 at sleeves 28' thereof for purposes of efficient reinforcement. It is to be particularly noted that the novel offsetting of said arms 26 and 27 gives a greater and a more uniform upper "shove" on jaw 20 than the type shown in Patents Nos. 1,699,084 and 1,904,575; this offsetting begins near the portions 14 and 15, Fig. 2. Cross bar 28 permits the use of a link composed of smaller cross section, thereby rendering the link sufficiently strong to cause movement of the movable jaw. The rearwardly offset arms 26 and 27 of the link also permit the movable jaw to separate from the upper stationary jaw a greater distance when the finger loops 12 and 17 are extended to the maximum extent. When the supporting and movable levers are extended by reason of the hereinbefore described novel structures, the clearance between the upper or stationary jaw and the lower or movable jaw is sufficient for the insertion of the eyelashes whether or not the eyelashes have been previously curled.

The upper stationary jaw 23 is expanded intermediate the ends thereof for purposes of greatly adding strength to the lower edge thereof to resist the upward thrust of the movable jaw. The supporting and movable levers at members 15, 16 and 10 and 11 respectively are opened spaced to eliminate the expedient of separating said members for purposes of enameling said members throughout their circumference.

It is distinctly understood that minor changes and variations may be resorted to from the standpoint of integration and nature of materials without departing from the spirit of the invention and without departing from the scope of the appended claims.

75 We claim:

1. In an eyelash curler as described having a stationary lever and a movable lever crossing and pivoting therewith, the said stationary lever having a fixed upper jaw and a lower movable jaw slidably mounted thereon, a linking structure 5 comprising diverging arms pivoting from the upper terminal of said movable lever and being rearwardly offset intermediate the length of said arms, the terminals of said arms being affixed to the lower edge of said lower movable jaw. 10
2. In an eyelash curler as described having a stationary lever and a movable lever crossing and pivoting therewith, the said stationary lever having a fixed upper jaw and a lower movable jaw slidably mounted thereon, a linking structure 15 comprising diverging arms pivoting from the upper terminal of said movable lever and being affixed at the free ends to the lower edge of said movable jaw, a reinforcing member connected between said diverging arms. 20
3. In an eyelash curler as described having a stationary lever and a movable lever crossing and pivoting therewith, the said stationary lever having a fixed upper jaw and a lower movable jaw slidably mounted thereon, a linking structure 25 comprising diverging arms pivoting from the upper terminal of said movable lever and being rearwardly offset intermediate the length of said arms, the terminals of said arms being affixed to the lower edge of said lower movable jaw, a 30 reinforcing member connected between said diverging arms.
4. In an eyelash curler as described having a stationary lever and a movable lever crossing and pivoting therewith, lower arms of said levers each 35 comprising juxtaposed and separated wire members joined at the lower ends of said wire members to form a finger loop.
5. In an eyelash curler as described having a stationary lever and a movable lever crossing and pivoting therewith, lower arms of said levers each 40 comprising juxtaposed and separated members, a finger loop continuously forming the said juxtaposed and separated members at the lower ends thereof. 45
6. In an eyelash curler as described having a stationary lever and a movable lever crossing and pivoting therewith, lower arms of said levers each comprising juxtaposed and separated members and connecting means at the lower ends of said juxtaposed and separated members to form a 50 finger hold.
7. In an eyelash curler as described having a stationary lever and a movable lever crossing and pivoting therewith, the said stationary lever having 55 parallel upright posts at one end thereof, an upper fixed jaw comprising a horizontally and curved strip of metal connected to said upright posts and having a rounded lower operative edge and an enlarged width intermediate the ends 60 of said fixed jaw.
8. In an eyelash curler as described having a stationary lever and a movable lever crossing and pivoting therewith, the said stationary lever having parallel upright posts at one end thereof, an 65 upper fixed jaw connected to said upright posts comprising a lower operative edge being rounded and curved horizontally and vertically, the said upper fixed jaw having an enlarged width intermediate the ends thereof. 70
9. In an eyelash curler, the combination of a stationary lever and a movable lever mounted thereon, a jaw secured to the upper end of said stationary lever, a slidable jaw mounted on said stationary lever and co-operating with said first- 75

mentioned jaw, and a link structure off-set near and pivotally connected at its lower end to said movable lever and having its upper end fixedly secured to said sliding jaw.

5 10. In an eyelash curler, the combination of a stationary lever and a movable lever secured thereto, said movable lever provided with an extension to one side of said stationary lever, a fixed jaw and a slidable jaw mounted on said stationary lever at the opposite side to said extension, and a link structure fixedly secured to said sliding jaw and extending down its greater portion upon the side of the stationary lever from which the jaw projects and connected to said 15 extension, whereby a more efficient upper movement of the sliding jaw is obtained in operation.

11. In an eyelash curler, the combination of a stationary lever and a movable lever pivotally

connected together, a fixed jaw on the upper end of said stationary lever, a slidable jaw flattened at its ends producing horizontal sleeves, said sleeves extending from the lower edge of said jaw and mounted to slide freely on said stationary lever, and means pivotally connecting said sliding jaw to said movable lever. 5

12. In an eyelash curler, the combination of a stationary lever and a movable lever pivoted thereto, a fixed jaw on said stationary lever, a 10 slidable jaw on said stationary lever, a link structure comprising separated portions, a cross bar provided at its ends with sleeves surrounding said separate portions, said link structure connected at its upper end to said sliding jaw, and connected at its lower end to said movable lever. 15
